UNITED STATES PATENT OFFICE.

JOHN T. SIMPSON, OF NEWARK, NEW JERSEY.

TIGHTENER.

1,423,162.

Specification of Letters Patent.

Patented July 18, 1922.

Application filed April 1, 1920. Serial No. 370,448.

To all whom it may concern:

Be it known that I, JOHN T. SIMPSON, a citizen of the United States, and a resident of Newark, in the county of Essex and State 5 of New Jersey, have invented a certain new and useful Tightener, of which the following is a specification.

This invention relates to tighteners in general and more especially to tighteners for 10 securing together the forms of concrete molds and the like.

Most of the tighteners operating similar to the embodiment of the present invention, for securing together the forms of concrete 15 molds, are provided with tightening devices intended initially to draw the forms into position, and then to be relieved by auxiliary locking devices whereupon the tightening devices would be removed for 20 drawing other forms into position. The expense of the tightening devices made it desirable to so use them. In view of the extra work involved in the use of the devices as aforesaid, one of the objects of the 25 present invention is to so simplify the construction with the consequent reduction in the cost of manufacture, that the tightening devices may be used to serve not only as the tightening element, but also as the 30 anchor for locking the forms in place during their use.

Specifically the invention further contemplates a tightening device which may be used with various dimensions of rods; which is 35 provided with means functioning to efficiently protect the threads of the device against admission of concrete or other foreign material, to guide the device, and to serve as a bearing for the nut acting portion 40 of the device; and which is provided with an extended operating surface to facilitate operating the device in places inconvenient for access.

Specifically one of the embodiments of the 45 invention contemplates an improved dog for anchoring the tightening device to the rod with which it cooperates, which dog is provided with a head that is adapted both to receive the blow of a hammer when driving 50 the dog into anchoring position, and is further adapted to receive the claws of the hammer for subsequently withdrawing the dog out of rod anchoring position.

These and other features, capabilities and 55 advantages of the invention will appear from the subjoined detail description of

specific embodiments of the invention illustrated in the accompanying drawings in which—

Figure 1 is a fragmental side elevation 60 showing a concrete mold equipped with one form of the present invention.

Figure 2 is a fragmental side elevation partly in section of the form of tightening device illustrated in Figure 1.

Figure 3 is a front end elevation of the device shown in Figure 2.

Figure 4 is an end elevation of the washer in position on the end of the tightening device.

Figure 5 is a fragmental side elevation showing a different form of dog than that illustrated in Figure 2; and Figure 6 is an end elevation of the dog illustrated in Figure 5.

In Figure 1 the form boards 7 are shown secured between cross bars 8 which are connected by tighteners constituting the present invention.

The tighteners each comprise a rod 9 preferably having a head 10 at one end to abut against a cross bar 8, the remainder of the rod being free to extend through cooperating cross bars 8, 8 and sufficiently projecting from the remote cross bar to receive the 85 tightening device generally designated as 11.

The tightening device comprises essentially an actuating member 12, a longitudinally movable member 13, and an anchoring member 14, for anchoring the movable member 13 to the rod 9. The actuating member 12 is internally threaded to receive the externally threaded portion of the movable member 13, and is provided, with an extended angular wrench seat 15 extending 95 substantially its entire length. The movable member 13 comprises essentially an elongated tubular member of sufficient internal diameter to receive various dimensions of rods 9, and is provided with bearing lugs 16 to receive between them the anchoring member 14, which is pivotally connected to the lugs 16 at their upper ends by means of the pin 17. The actuating member or dog 14 has a lower cam face 18 for biting into the 100 rod 9 when driven toward the actuating member 12 in the direction of the dotted line position indicated in Figure 2.

The lugs 16 are formed at the free end of the movable member 13 and form the terminal continuations of the reinforcing annular bead 19 formed on such end of the

movable member. The movable member 13 as shown in Figure 2, to accommodate the dog is recessed beyond lugs 16, and the external threads on the movable member 13 terminate a substantial distance from the dog recess thus to insure the proper operation of the device.

In Figure 2, the dog there shown is provided with a T-head 20 which may serve to receive the blow of a hammer when driving the dog into biting position and in turn the ears 21 of the T-head may serve to cooperate with the claws of a hammer when removing the dog out of engagement with the rod.

The end of the actuating member 12 is provided with an enlargement 22 to receive the washer 23 which preferably comprises a disc portion 24 and fingers 25 for engaging the enlargement 22 as shown. The washer 23, by snugly engaging the rod 9, will prevent the admission of concrete or other foreign material to the threads of the actuating member 12 and movable member 13 and will also serve to engage a bar 8 and thus form a bearing for the actuating member 12, thereby guarding against the grinding of such actuating member 12 into the bar 8 so obnoxious when the bar 8 is composed of wood or the like.

The dog 26 shown in Figures 5 and 6 has an upward extension 27 instead of the T-head 20 of the dog 14. In this embodiment, the extension 27 may serve both to receive the blow for biting the dog into the rod, and also to receive the blow for withdrawing the dog out of engagement with the rod.

It is obvious that various changes and

modifications may be made to the details of construction, without departing from the general spirit of the invention.

Having thus described the invention what is claimed as new and desired to be secured by Letters Patent, is:—

1. A device of the class described having an internally threaded tubular actuating member, an externally threaded tubular movable member adapted to receive a rod, an anchoring member on said movable member for anchoring said movable member in place on the rod, an enlargement on the end of said actuating member, a washer, and fingers on said washer for engaging said enlargement, said engagement permitting relative rotation of the washer and actuating member.

2. A device of the class described having an internally threaded tubular actuating member, an externally threaded tubular movable member, a dog, lugs on said movable member, there being a recess in said movable member registering with said lugs to receive said dog, a pin for pivotally connecting the dog to said lugs, and a T-head on said dog functioning both to receive the blow of a hammer when driving the dog into position and to cooperate with the claws of a hammer when removing the dog out of engaging position.

This specification signed and witnessed this 24th day of March, 1920.

JOHN T. SIMPSON.
